UNITED STATES PATENT OFFICE.

WILLIAM W. DEAN, OF ELYRIA, OHIO; CURTIS B. CAMP, TRUSTEE, APPOINTED BY COURT.

HARMONIC SIGNALING DEVICE FOR TELEPHONE SYSTEMS.

1,125,493.

Specification of Letters Patent.

Patented Jan. 19, 1915.

Application filed September 9, 1905. Serial No. 277,686.

To all whom it may concern:

Be it known that I, WILLIAM W. DEAN, a citizen of the United States, residing at Elyria, in the county of Lorain and State of Ohio, have invented certain new and useful Improvements in Harmonic Signaling Devices for Telephone Systems, of which the following is a specification, reference being had therein to the accompanying drawing.

10 My invention relates to harmonic selective signaling, and particularly to signal receiving devices therefor. Specifically stated, it has to do with the ringers at the substations on a polystation telephone line, and it 15 has for its object the improvement of such devices as will be fully set forth hereinafter.

The essential features of my present ringer are, a stiff frame or yoke carrying the magnet cores, the gongs, and the permanent 20 magnet used for polarizing the cores, pole pieces carrying a yoke, the yoke carrying the transverse spring, and the spring carrying the armature which in turn carries the clapper-rod and clapper. This clapper-rod and 25 clapper constitute the tuned reed upon which I depend for determining the characteristic pitch of the individual ringer, and the yoke, spring and reed are so related that under normal conditions the clapper-rod 30 and clapper are maintained in approximately a median position between the gongs. In determining the pitch of any tuned body there are three factors to be considered, viz. the length, the mass, and the degree of tension. The mass of my reed is determined by the length and weight of the clapper as well as of the rod itself, the 35 length of the reed is determined by the position of the clapper on the clapper-rod, and the tension is determined by the stiffness of the spring which supports the armature and reed.

My invention is illustrated in the accompanying drawings, in which—

40 Figure 1 is a top plan view of a ringer embodying the invention: Fig. 2 is a side view of the same: and Fig. 3 is a detail.

In the drawings A designates the ringer magnets, wound on the cores a' and a'' , which are joined as well as carried by the iron yoke a upon whose terminal extensions a' are pivoted segments a'' carrying the gong posts c of the gongs C, and adjustable by means of the micrometer screws a'' working 50 in the drop ears a^4 , a^5 . The yoke also carries the permanent magnet a^3 which extends 55

down behind the electro-magnets and beneath the armature, which as well as the magnet cores it polarizes constantly.

Upon and across the free ends of the magnet cores a' and a'' I mount a yoke B, adjustable up or down by means of the nuts b . I preferably make this mounting and adjustment upon a sleeve around the core, but as the same forms no part of my present invention this manner of mounting is immaterial. The yoke, with a transverse or cross portion b^{50} has boudly returned ends b^5 . The major axis of the yoke lies in a line passing through the center of the core ends, 60 and the minor or cross axis lies at right angles thereto. The armature b' , which is of soft iron, lies parallel to the major axis of the yoke and has a cross portion or extension b^{10} lying along the minor axis of the 65 yoke and carrying the clapper-rod b^3 , preferably riveted to it. Upon the downturned ends b^5 of the cross yoke I secure a flat leaf spring b^2 . This is shown as screwed on, but obviously it may be held by rivets or in any 70 other suitable manner. Between this spring and the yoke I place the armature, and secure it to the spring, the securing means shown being screws. Directly between the 75 pole pieces, I form an opening b^9 in the armature, and into this I enter the end of a pivot screw b^7 tapped into the yoke b^{50} and locked when adjusted by a nut b^8 . The purpose of this screw is to give a pivot bearing 80 for the armature to turn upon, and as the movement of the armature is dependent upon a torsional strain of the spring in one 85 direction or the other, the pivot point lies in the plane and against the upper face of the 90 spring.

95 The operation of my improved signaling device or ringer is almost obvious from the description. The three factors of length, mass and tension are secured by means of the clapper rod b^3 in its length and mass, the 100 clapper b^4 in its length and mass, and the tension by the spring b^2 . The movement of the armature upon the point of the screw b^7 is perfectly smooth and satisfactory, and owing to the nature and stiffness of the 105 parts a perfect adjustment can be made with very little difficulty. When current of the proper frequency passes through the windings A, the armature b' receives repeated pulls upon its alternate ends which 110 quickly set it into active vibration, until the clapper b^4 is thrown against the gongs.

Any other frequency than the proper one leaves the armature undisturbed.

Having thus described my invention what I claim and desire to secure by Letters Patent is:

1. A harmonic ringer comprising an electromagnet, a gong, a clapper rod and clapper, an armature rigidly associated with such clapper rod, a prismatic spring adapted to receive support from its ends and to carry such armature intermediate of its ends, such spring lying in a plane substantially parallel with such armature and adapted to be twisted when such armature is energized, and means for preventing such spring bending due to the attraction of such electromagnet.
2. A harmonic ringer comprising an electromagnet, a gong, a clapper rod and clapper, an armature rigidly associated with such clapper rod, a yoke secured to the operating end of such electromagnet, a prismatic spring supported at its ends from such yoke and to carry such armature intermediate of its ends, such spring lying in a

plane substantially parallel with such armature and adapted to be twisted when such electromagnet is energized and a pivot for such spring intermediate its ends.

3. A harmonic ringer comprising an electromagnet, a pair of gongs, a clapper rod and clapper, an armature rigidly associated with such clapper rod, a yoke secured to the operating end of such electromagnet, a prismatic spring supported at its ends from such yoke and to carry such armature intermediate of its ends, such spring lying in a plane substantially parallel with such armature and adapted to be twisted when such electromagnet is energized, such spring adapted to normally maintain such clapper intermediate and out of contact with such gongs and a pivot for such spring intermediate its ends.

In testimony whereof I affix my signature in presence of two witnesses.

WILLIAM W. DEAN.
